ABRASIVE-PROOF BOBBIN

Harry D. Clinton, Johnson City, N. Y.

Application February 11, 1939, Serial No. 255,973

7 Claims. (Cl. 242—123)

This invention relates to spools or bobbins and the like, or to improvements in the same, having reference more particularly to textile spools and bobbins used for various purposes in different textile mills.

One of the objects is to provide a spool or bobbin with a head which will not dent, crack or break easily from the rough usage and handling which these articles receive in the mills. Dents and other abrasions in the rims of the heads, caused by striking against hard edges or against other spools from tossing and knocking about, tend to catch or snag and break the yarn in loading and unloading such spools, especially if the yarn is drawn over or around the heads. Operations accordingly must be interrupted, sometimes quite frequently, in order to repair the breaks in the yarn, which of course hampers and greatly impairs factory production. It is therefore desirable, and indeed essential to have a spool with a head which has a perfectly smooth well-rounded rim and which in said rim is substantially abrasive-proof, or maintains its smoothness resistant to and unmarred by the knocks and drops to which these spools are subjected, under normal conditions of use and even from hard blows. The invention aims to provide a spool or bobbin head of such character.

Another object is to provide a spool or bobbin combining a head of the stated character with all necessary strength and durability, so that it will not loosen or come apart nor break, unless deliberately smashed with crushing blows, and will last useably for a prolonged period of time.

A further object is to provide a spool or bobbin head which will be substantially stain-proof and/or also corrosion or rust proof, so as to prevent possible discoloration or soiling of the yarn coming into contact with the same. In this connection, heads of a polished surface property or finish are more generally desirable.

Other objects will be set forth or appear in the following specification, from which a full understanding of the invention and the advantages attained thereby will be gained best by description with reference to the attached drawing, illustrating the same in one practical embodiment of a textile bobbin.

In said drawing:

Fig. 1 is a vertical elevation or side view of a bobbin shown broken away intermediately with its opposite ends in contracted relation, the upper portion representing a head or end flange of the invention applied to one end and the lower por-

tion representing an ordinary head applied to the other end;

Fig. 2 is a side view illustrating a possible modification of the lower end head into a "twister bobbin" formation;

Fig. 3 is a vertical diametrically sectional view of the upper end portion of Fig. 1; and

Fig. 4 is a plan or front face view of the upper end head (of the invention) detached.

At the outset, it should be stated that the invention broadly consists in the provision of a spool head of an all-integral or single-piece plate material, the marginal or peripheral edge portion of which is rendered substantially abrasive-proof by a hardening to a degree materially greater than that of its remainder or central portion; that is, a head of solid composition having a considerable differential of hardness between its peripheral edge and central body parts. Thus, it may include any spool or bobbin head composed of a plate or sheet material in which the marginal portion providing the peripheral edge is given an increased requisite degree of hardness above that of its natural state as constituted or embodied in its remainder portion.

In the illustrative embodiment, the head, indicated as a whole by the numeral 5, comprises a circular piece of pressed metal plate—preferably a piece of stainless and corrosion-resistant steel commonly identified as "18-8" stainless steel, meaning 18% chromium and 8% nickel in its composition. This head, at any suitable stage of its fabrication, is subjected in the peripheral or marginal portion to a plastic deformation within the cold forming range, so as to work-harden said portion and to establish a marginal area of optimum hardness in the same. Such deformation is preferably effected by a marginal rolling or drawing inwardly, as in the present instance. However, other methods of such deformation, or bending or rolling, may be employed, such as cupping or flanging. Since the corrosion-resistant steels here contemplated are solid solution alloys, this deformation is attended with a rapid hardening and with a concomitant increase in tensile strength in the cold-worked areas. Whenever the exigencies of a particular use so demand, the work-hardened material may be subjected to a light anneal to relieve internal stresses, without appreciable loss of hardness. Such light anneal also presents the supplementary advantage of reducing corrosion susceptibility of the work-hardened portions.

The described operation in forming the head 5 establishes a backwardly bent, top-overextending 65

lip or flange 5^a around its circumferential extent, thereby providing a work-hardened peripheral edge or rim 55 thereto which is smooth and well-rounded and has an exceptional hardness or abrasive resistant texture. That is, the plate or piece around its marginal portion is treated so as to render it or its peripheral edge of a degree of hardness greatly exceeding that of its remainder or central portion, or of the material itself in 10 the natural state, as determined by Brinell or other measuring tests.

The said head or plate piece 5 is advantageously pressed into formation with a slightly sloping wall or face 5^b in its central or main body portion, 15 somewhat like an ordinary table dish, thereby affording easier means or facility for the yarn to be drawn off over its rim in the direction of the bobbin or barrel axis. Of course it might instead be formed flat if so desired, as in some cases perhaps it would be. For ready affixture to the barrel, a neck portion or sleeve 5^c is provided upon and integral with its central part, said neck or sleeve extending axially from its orificial center and adapted to fit into a recess or counterbore 20 formed therefor in the barrel end. This neck or sleeve portion may advantageously be provided with a series of ribs or teeth 5^c to engage tightly and non-rotatively in the material of the surrounding barrel end.

30 The described head is attached to one or both ends of the bobbin barrel, indicated by 6, in a manner which will be readily understood. In the present instance this is done by the usual fastening plug 7 as represented in Fig. 3. That is, the plug, having an overextending outer flange (not referenced), is passed through the central orifice of the head and registering neck 5^c thereof and clamps the head to the end of the barrel by a combined friction and glue fit into the end or counterbore of the barrel. It is unnecessary to describe this affixture in fuller detail since it is a common and well-known means of applying a head to a barrel and no novelty is claimed in such affixture per se. However, it may be found advantageous to provide a metal ferrule or wear sleeve 8 in the central bore of the plug, or in the central bore of the barrel, or both, to eliminate gudgeon wear upon the material of these parts, which are usually formed of wood.

50 In the illustrated construction, the lower end of the barrel carries an ordinary flat head 9, of greater diameter than the described head 5, which may be formed of any suitable material but is preferably composed of hard vulcanized fibre 55 which has been found to be very advantageous for many purposes. If desired, this lower end head may be modified into a twister-head for "twister bobbin" use, by applying segment pieces 10 to the outer face thereof, or the entire head may be substituted by application of a flat head like said head 9 having these segmental pieces 10 formed integrally with the same, thus providing a notch 11 adapted to fit the ordinary driving lug of a twister spindle. As another alternative of course 60 a head 5 of the invention may be applied to said lower end of the barrel in substitution for either of the ordinary heads just described. Whether or not this is done will depend upon the use to which the bobbin is to be put.

70 Thus is provided a spool or bobbin with an all-integral head having a substantially abrasive-proof rim produced by a treatment of its marginal or peripheral edge portion so as to give it a degree of hardness greatly exceeding that of its remainder or central portion, and likewise exceed-

ing that of the component material in its natural or untreated state. So exceptionally hard is the rim of the described example rendered that it may be struck quite forcibly against or by different surfaces, and even against sharp edges, without showing any sign of dent or impress or any kind of fracture. Its smooth well-rounded surfacing remains unmarred and unblemished and this condition is maintained for an indefinite time unless the article is deliberately smashed by irresistible blows or crushing.

The advantages of this invention will be readily realized and appreciated by those familiar with these constructions and particularly by mill operators who are constantly annoyed by yarn breakages and the necessity of replacing worn and damaged bobbins with new or repaired ones. It substantially reduces, if it does not entirely eliminate, the waste and loss in production from the need of stopping the looms and other machinery 20 to repair breaks and make substitutions. It insures a smooth and free feed of the yarn and minimizes the possibility of discoloring or soiling it from contact with the bobbin or spool head. All of these will be recognized by those experienced in this art.

As the invention may be applied in various ways and may be embodied in various forms, with different variations in the specific manner or process by which its results are attained, it is not 30 intended to be limited by the appended claims to the specific article or to the specific form, composition or treatment herein described with reference to the illustrative example. In this connection, also, the term "bobbin" as hereinafter used 35 is intended to cover also a spool, cop or any such like article of manufacture used as a reel or loading element.

Having thus described my invention, what I claim as new and desire to secure by Letters Patent of the United States is:

1. A bobbin or the like having an end head comprising a plate piece of stainless steel having its marginal edge portion rendered substantially abrasive-proof by a cold-rolling work-hardening treatment imparting thereto an increased degree of hardness considerably exceeding that of its remaining central body portion.

2. A bobbin or the like having an end head comprising a plate piece of chromium-nickel steel having its marginal edge portion rendered substantially abrasive-proof by a work-hardening cold-rolling treatment imparting thereto a high degree of hardness as compared with its remaining central body portion.

3. A bobbin or the like having an end head comprising a plate piece of chromium-nickel composition steel having its marginal edge portion rendered substantially abrasive-proof by a work-hardening rolling treatment within the cold forming range imparting thereto a high degree of hardness as compared with its remaining central body portion.

4. A bobbin or the like having an end head comprising an all-integral plate piece of stainless steel metal having its marginal edge portion rendered substantially abrasive-proof by a work-hardening rolling treatment within the cold forming range thereof imparting thereto a high degree of hardness in said edge as compared with that of its remaining central body portion.

5. A bobbin or the like having an end head comprising an all-integral plate piece of steel of the 18% chromium—8% nickel type stainless

steel, the marginal edge portion of which is rendered substantially abrasive-proof by a plastic deformation attained by a work-hardening rolling treatment thereof performed within its cold forming range, imparting thereto a high degree of hardness as compared with the remaining central body portion of the piece.

6. A bobbin or the like having an end head comprising a plate piece of stainless sheet steel having its marginal edge portion rolled in a work-hardening operation into formation of a backwardly directed top-overextending flange providing a smooth well-rounded rim thereto and imparting to said rim an increased degree of hardness materially greater than that of its remain-

ing central body portion rendering said rim substantially abrasive-proof.

7. As an article of manufacture, a bobbin or the like head comprising a substantially dish-shaped plate piece of stainless sheet steel having a certain natural hardness, said piece having its marginal edge portion rounded and smoothed by a work-hardening rolling treatment into the formation of a suitable rim rendered substantially abrasive-proof by said treatment 5 imparting thereto an increased degree of hardness considerably greater than that of the remaining central portion of the piece and of the steel thereof itself in the natural state.

HARRY D. CLINTON. 15
